UNITED STATES PATENT OFFICE.

HENRY BRYDA, OF WOONSOCKET, RHODE ISLAND.

SLEIGH.

SPECIFICATION forming part of Letters Patent No. 761,653, dated June 7, 1904.

Application filed February 15, 1904. Serial No. 193,722. (No model.)

To all whom it may concern:

Be it known that I, HENRY BRYDA, a citizen of the United States, residing at Woonsocket, in the county of Providence and State of Rhode Island, have invented certain new and useful Improvements in Sleighs; and I do declare the following to be a full, clear, and exact description of the invention, such as will enable others skilled in the art to which it appertains to make and use the same.

This invention relates to improvements in sleighs.

The object of the invention is to provide a sleigh having means whereby the same may be propelled over the ice or snow.

A further object is to provide means whereby the sleigh may be steered or turned in one direction or the other, and also to provide means for quickly stopping the same.

With these and other objects in view the invention consists of certain novel features of construction, combination, and arrangement of parts, as will be more fully described, and particularly pointed out in the appended claims.

In the accompanying drawings, Figure 1 is a side view of a sleigh constructed in accordance with my invention. Fig. 2 is a top plan view, Fig. 3 is a bottom plan view, Fig. 4 is a rear end elevation, and Fig. 5 is a vertical longitudinal sectional view, of the same. Fig. 6 is a vertical transverse sectional view looking toward the rear end of the sled. Fig. 7 is a detail view of one of the push-rods. Fig. 8 is a similar view of one of the push-rod brackets or hangers.

Referring more particularly to the drawings, 1 denotes a sleigh, which may be of any suitable construction, but which is here shown as a flat sled having the usual runners 2, upon which is supported a frame 3, consisting of uprights or standards 4, connected at their upper ends by cross-bars 5, which support longitudinally-disposed side rails 6, on which are adapted to rest the upper platform 6' of the sled.

Below the upper platform 6' is arranged a lower platform 7, and to the standards 4 and the edges of the platform 7 are secured side pieces 8, thereby forming a box or body. The

runners and side rails are suitably braced to the standards 4 by brace bars or rods 9.

To the cross-bars 5 are connected longitudinally-disposed angle-iron beams 10, on which, near the rear end of the sled, are secured bearings 12, in which are mounted a transversely-disposed crank-shaft 13, having fixed thereon a sprocket-wheel 14 and a fly-wheel 15. A sprocket-chain 16 connects the sprocket-wheel 14 with the sprocket-wheel of an engine 17, arranged in the forward end of the machine.

On the ends of the shaft 13 are fixed oppositely-disposed crank-arms 18, to which are connected pitman-rods 19, the opposite ends of which are connected to cross-heads 20, which are slidably mounted in guides 21, secured to the beams 10. To the cross-heads 20 are also secured rearwardly-projecting downwardly-inclined push-bars 22, the outer ends of which are beveled or pointed, as shown, to facilitate the engagement of the same with ice. On the bars 22 near their outer ends are slidably mounted snow-engaging plates 23, which are normally pressed outwardly against a stoppin 24 by springs 25, which are coiled around the push-rods between said plates and a stoppin 26.

By the use of the plates 23 the sled may be pushed through soft snow, into which the push-bars would otherwise be forced and would exert but little propelling power on the sled. The coiled springs 25 will allow the plates 23 to give slightly when they engage the snow on the outward thrust of the push-bars, but upon the reverse movement of the rods will force the plates outwardly against the stoppin 24, which will jar the snow that may have stuck to the plates off from the same, thereby preventing them from becoming clogged up.

The push-bars 22 are connected to one end of coil-spring 27, the opposite ends of which are connected to the sides of the sled, said springs being adapted to aid in retracting the push-bars. Said push-bars are formed in two sections and are jointed about midway their length to permit the outer section of either to be swung in laterally toward the center of the sled, which will cause the sled to be turned in the direction of the inwardly-projecting bar

by reason of the fact that this bar is now shorter than the one on the other side and also engages the ground near the center of the sled, and therefore does not offer any resistance to the bar on the opposite side, thus permitting the same to push the head of the sled round in a circle.

In order to swing the ends of the push-bars inwardly to turn or steer the sled when desired, a suitable controlling mechanism is provided, which consists of a longitudinally-disposed rock-shaft 28, journaled in the frame of the sled. On the forward end of the rock-shaft is fixed an upwardly-projecting handle 29, and to the rear end of the shaft is connected a cross bar or head 30, to the ends of which are pivotally connected vertically-disposed link-rods 31, in the lower ends of which are formed elongated slots 32. In said slots are disposed the free ends of brackets or hangers 33, which are pivotally connected to the rear end of the sled-frame and are provided with downwardly-extending loops 34, which engage the lower ends of the push-bars and serve as supports and guides for the same and which when the shaft 28 is turned will be rocked by the link-rods 31 to swing the lower end of one or the other of the push-bars inwardly. The slotted connection of the link-rods with the free ends of the brackets or hangers will permit one of said link-rods to lower without engaging said end of the adjacent bracket while the opposite link-rod is raising and rocking the bracket adjacent thereto to cause the end of the push-rod on this side of the sled to swing inwardly. Coiled springs 35 are connected to the side of the hangers 33 and to the side of the sled-frame, whereby said hangers will be quickly swung back to restore the parts to their normal position when the lever 29 on the rock-shaft 28 is released.

On the under side of the lower platform 7 is arranged a brake mechanism consisting of a pair of arms or levers 36, connected at their upper ends to a cross-bar 37, rotatably mounted in bearings on the under side of the lower platform 7. The arms or levers 36 are also connected together by a centrally-disposed cross-bar 38, to which is connected an upwardly and forwardly curved lever 39, which extends above the upper platform and forms a handle whereby the arms or levers 36 may be turned down to engage the lower ends of the same with the ice or snow to form a brake to slacken the speed or to entirely stop the sled. Coiled springs 40 are connected to the arms or levers 36 and to the bottom of the platform 7, by which said arms are raised and normally held up against said platform when the lever or handle 39 is released.

The lower ends of the arms or levers 36 are curved downwardly and flattened to form blades, which are adapted to engage the ice or snow. At a suitable point on the sled is

arranged a gasoline-tank from which gasoline is supplied to the engine.

The runners of the sled are provided with the usual shoes, which are sharpened after the manner of a skate-runner to keep the sled in a straight course except when being turned by the steering mechanism.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus described my invention, what I claim as new, and desire to secure by Letters Patent, is—

1. In a sleigh of the character described, the combination with the runners having a suitable supporting-frame mounted thereon, of a propelling mechanism supported by said frame, said mechanism comprising a suitably-mounted crank-shaft, means for driving the same, cranks fixed on the ends of said shaft, pitman-rods connected to said cranks, slidably-mounted cross-heads connected to the ends of said pitman-rods, push-rods connected to said cross-heads and adapted to be reciprocated by the same, means whereby said push-bars may be manipulated to steer said sled, and a brake mechanism carried by the same, substantially as described.

2. In a sleigh of the character described, the combination with the runners having a suitable supporting-frame mounted thereon, of a propelling mechanism supported by said frame, said mechanism comprising a suitably-mounted crank-shaft, means for driving the same, cranks fixed on the ends of said shaft, pitman-rods connected to said cranks, slidably-mounted cross-heads connected to the ends of said pitman-rods, jointed push-rods connected to said cross-heads and adapted to be reciprocated by the same, pivoted brackets or hangers to support said push-bars, means for rocking said brackets or hangers inwardly to swing the outer ends of said push-bars in toward the center of said sled to turn the same, and means for restoring said parts to their normal positions, substantially as described.

3. In a sleigh of the character described, the combination with the runners having a suitable supporting-frame mounted thereon, of a propelling mechanism supported by said frame, said mechanism comprising a suitably-mounted crank-shaft, means for driving the same, cranks fixed on the ends of said shaft, pitman-rods connected to said cranks, slidably-mounted cross-heads connected to the ends of said pitman-rods, push-rods connected to said cross-heads and adapted to be reciprocated by the same, snow-engaging plates carried by said

push-bars, and means whereby the same are prevented from becoming clogged with snow, substantially as described.

4. In a sleigh of the character described, the combination with the runners having a suitable supporting-frame mounted thereon, of a propelling mechanism supported by said frame, said mechanism comprising a suitably-mounted crank-shaft, means for driving the same, cranks fixed on the ends of said shaft, pitman-rods connected to said cranks, slidably-mounted cross-heads connected to the ends of said pitman-rods, jointed push-rods connected to said cross-heads, and adapted to be reciprocated by the same, means for swinging the lower ends of said push-bars inwardly toward the center of said sled to turn the same in one direction or the other, and spring-controlled snow-engaging plates arranged near the outer ends of said push-rods, substantially as described.

5. In a sleigh of the character described, the combination with the runners having a suitable supporting-frame mounted thereon, of a propelling mechanism supported by said frame, said mechanism comprising a suitably-mounted crank-shaft, means for driving the same, cranks fixed on the ends of said shaft, pitman-rods connected to said cranks, slidably-mounted cross-heads connected to the ends of said pitman-rods, jointed push-rods connected to said cross-heads and adapted to be reciprocated by the same, pivoted brackets or hangers to support said push-bars, a longitudinally-disposed rock-shaft journaled in said frame, a cross-head fixed on one end of the same, link-rods pivotally connected at their upper ends to the ends of said cross-head and having a loose connection with said brackets or hangers at their lower ends whereby upon turning said rock-shaft, said hangers may be rocked to swing the outer ends of said push-rods inwardly toward the center of said sled to turn the same in one direction or the other, and means for restoring said parts to their normal positions, substantially as described.

6. In a sleigh of the character described, the combination with the runners having a suitable supporting-frame mounted thereon, of a propelling mechanism supported by said frame, said mechanism comprising a suitably-

mounted crank-shaft, means for driving the same, cranks fixed on the ends of said shaft, pitman-rods connected to said cranks, slidably-mounted cross-heads connected to the ends of said pitman-rods, jointed push-rods connected to said cross-heads and adapted to be reciprocated by the same, pivoted brackets or hangers to support said push-bars, means for rocking said brackets or hangers inwardly to swing the outer ends of said push-bars in toward the center of said sled to turn the same, and means for restoring said parts to their normal positions, brake arms or levers pivotally connected to the frame of said sled, means whereby said arms are normally held up from engagement with the ice or snow and means for forcing the same down into engagement with the same to stop said sled, substantially as described.

7. In a sleigh of the character described, the combination with the runners having a suitable supporting-frame mounted thereon, of a propelling mechanism supported by said frame, said mechanism comprising a suitably-mounted crank-shaft, means for driving the same, cranks fixed on the ends of said shaft, pitman-rods connected to said cranks, slidably-mounted cross-heads connected to the ends of said pitman-rods, jointed push-rods connected to said cross-heads and adapted to be reciprocated by the same, pivoted brackets or hangers to support said push-bars, means for rocking said brackets or hangers inwardly to swing the outer ends of said push-bars in toward the center of said sled to turn the same, and means for restoring said parts to their normal positions, brake-arms connected by an upper cross-bar, and hingedly connected to said sled-frame, springs to retract and normally hold said arms up, and an operating lever or handle connected to said arms, whereby the same may be turned down into engagement with the snow or ice to stop said sled, substantially as described.

In testimony whereof I have hereunto set my hand in presence of two subscribing witnesses.

HENRY BRYDA.
